UNITED STATES PATENT OFFICE.

JOHN RING, OF ST. LOUIS, MISSOURI.

APPARATUS FOR PURIFYING THE AIR IN SUBWAYS.

No. 922,953.

Specification of Letters Patent. Patented May 25, 1909.

Application filed October 21, 1907. Serial No. 398,414.

To all whom it may concern:

Be it known that I, JOHN RING, a citizen of the United States of America, residing at the city of St. Louis, in the State of Missouri, 5 have invented certain new and useful Improvements in Apparatus for Purifying the Air in Subways, of which the following is a full, clear, and exact description, reference being had to the accompanying drawings, 10 forming part of this specification.

My invention relates to an apparatus for purifying air in subways such as are utilized in the operation of underground railroads and in which the outer air is sought to be 15 brought in by every possible means and has free ingress and egress and is drawn in, stirred up with the dust in the tunnel and expelled by the movement of the cars passing therethrough.

20 In the operation of subway railroads at the present time very unsatisfactory sanitary conditions exist in the atmosphere that must be breathed by the passengers transported in the railroad cars and the odors due 25 to such unsanitary conditions are found so objectionable to the senses of the passengers as to render travel in the subways unpleasant and improvements in the condition of such atmosphere are imperatively necessary. 30 The conditions mentioned are made more manifold due to the high temperature of the atmosphere in the subway, caused mainly by the enormous expenditure of electric energy utilized for the operation of the railroad cars 35 and consequent to frictional contact between the car wheels and the railroad rails. This high temperature tends to aggravate the unpleasant conditions in the subways and greatly increases the possible dangers to the 40 health of the passengers resulting from the close contact of vast numbers of people of all kinds and conditions and living, many of them, under unsanitary surroundings when not in the course of travel in the subways.

45 Numerous efforts have heretofore been made to overcome the objectionable features that have been recited, such as through the use of blow holes or vents leading from the subway to the exterior atmosphere, and the 50 use of blowers or fans, but these efforts have resulted only in a partial elimination of the objectionable conditions and therefore have not proven satisfactory agencies for the correction of the objectionable conditions.

55 For the purpose of eliminating the unsatis-

factory conditions of the atmosphere in such subways I have devised the system of air purification to be herein described and which may be briefly set forth as follows: Air is taken from the atmosphere exterior of the 60 subway at as high a point above the earth as practicable, compressed to a high pressure, then passed through cooling coils for the purpose of reducing the heat of the air, which, under compression, has become sensible heat, 65 to latent heat, or, in other words, to atmospheric temperature. The compressed and cooled air is then delivered into a storage reservoir and from said storage reservoir is conducted to a distribution point. At this 70 last named point the air enters into expansion pipes situated in the subway and open to communication therewith. The expansion pipes are controlled by expansion valves and they are continued to sufficient lengths 75 in the subway to afford refrigerating surfaces to cool the air in the subway by the absorption of heat therefrom and due to the expansion of the compressed air while escaping through the expansion valves into the expansion pipes. The air, as it escapes into the subway and mixes with the air previously present therein, still retains the power 80 of abstracting heat from the air present in the subway and it is quickly distributed 85 throughout the subway due to the continual disturbance of air in such subway caused by the passing railroad cars that act to impel the air in one direction and cause an opposite movement thereof by the suction occasioned during the movement of the cars. 90 As a consequence, the atmosphere in the subway is effectually purified and is also cooled and furthermore the impurities, such as organic substances, that are present in the air 95 in the subway are attracted to the moisture (frost) which is created upon the expansion pipes, due to refrigerating action in said pipes and said impurities are absorbed by the moisture mentioned, thereby eliminating them 100 from the air which must be constantly breathed by passengers while being transported in the railroad cars operated in the subway.

My apparatus comprises the appliances 105 illustrated in the accompanying drawings, and in which:

Figure I is an elevation of the air compressing, cooling and storage devices of the apparatus, Fig. II is an elevation of the 110

expansion device of the apparatus. Fig. III is in part an enlarged and in part a vertical section of the cooling device of the apparatus. Fig. IV is a top or plan view of the drip pan 5 surmounting the air cooling device. Fig. V is in part an enlarged top or plan view of one of the expansion pipes utilized in the apparatus and in part a cross section through the header to which the series of expansion pipes 10 are connected. Fig. VI is a perspective view of a subway partly broken out and my apparatus therein.

In the accompanying drawings: 1 designates an air supply pipe that is open at its 15 upper end and extends to a sufficient height in the open atmosphere to receive the air that is to be passed through the apparatus. This supply pipe leads to an air compressor 2 of any ordinary description that is operated 20 by a suitable engine 3.

4 is a conducting pipe leading from the air compressor and through which compressed air is delivered to a cooling coil 5.

For the purpose of reducing the temperature 25 of the compressed air to atmospheric temperature instead of sensible heat while passing through the cooling coil, I mount above the cooling coil a series of drip pans 6 from which a flow of water may constantly 30 descend upon the cooling coil and fall into a catch basin 7. The cooling coil preferably consists of a plurality of coiled pipe sections that are united at their inlet ends to a header 5' to which the conducting pipe 4 extends 35 while the outlet ends of the coils are connected to a header 5".

8 is a conducting pipe leading from the header 5".

9 designates a storage reservoir to which 40 the conducting pipe 8 is connected and in which the cooled compressed air is stored.

10 are receivers having communication 45 with the storage reservoir and which are intended to be cut off, when desired, from such communication by valves 11. These receivers are provided with drain cocks 12. The receivers are designed to be normally in communication with the storage reservoir in order that the condensed moisture that 50 enters into the storage reservoir may be drained therefrom into the receivers. This moisture which is condensed by the compression of the air absorbs many impurities in the air that are soluble in water and consequently by delivering the moisture into 55 the receivers it is removed from the circuit traversed by the air flowing through the ap-

paratus in order that the impurities may not be again taken up by the air.

13 designates a main leading from the storage reservoir, and 14 is a valve by which the flow of air from the storage reservoir to the main may be controlled. The main 13 leads into the subway in which the air is to be purified and it has connected to it any desirable number of headers 15 in which are cut-off valves 16.

17 are expansion valves connected to the headers, and 18 are expansion pipes connected to said valves and having greater interior 70 area than the ports in said valves. The expansion pipes are suitably supported in the subway, within which the air is to be purified, and they are open at their ends farthest removed from the expansion valves in order that the air may escape freely through said open ends into the subway to be distributed therein for the purification of the foul air in the subway.

I claim:

The combination, with a railway subway open at both ends and having the usual ventilating shafts and air outlets and in which the air has free ingress and egress and is drawn in, stirred up with the dust therein 85 and expelled by the movement of the cars passing therethrough; of an air supply stand pipe open at its upper end and extending to a sufficient height in the open atmosphere, an air compressor with which the stand pipe 90 connects, a conducting pipe leading from the air compressor, a cooling coil with which the conducting pipe connects, a series of drip pans for water located above the cooling coil, a catch basin for the water located beneath 95 the cooling coil, a conducting pipe leading from the cooling coil, a storage reservoir for the cooled and compressed air, with which the conducting pipe from the coil connects, receivers having controlling valves and connected with the storage reservoir, a main leading from the storage reservoir having a controlling valve, and a series of headers with which the main connects, provided with cut-off valves, expansion valves connected to the headers and expansion pipes connected with the expansion valves and having greater interior area than the ports of the expansion valves.

JOHN RING.
